UNITED STATES PATENT OFFICE.

FRIEDRICH KALKNER, OF NUERMBERG, GERMANY, ASSIGNOR TO SIEMENS-SCHUCKERT
WERKE G. M. B. H., OF BERLIN, GERMANY, A CORPORATION OF GERMANY.

ELECTRODE FOR ARC-LAMPS.

No. 916,877.

Specification of Letters Patent. Patented March 30, 1909.

Application filed August 11, 1908. Serial No. 447,965.

To all whom it may concern:

Be it known that I, FRIEDRICH KALKNER, a subject of the German Emperor, and residing at Nuremberg, Germany, have invented 5 certain new and useful Improvements in Electrodes for Arc-Lamps, of which the following is a specification.

The present invention relates to arc lamps for large currents, particularly such as are 10 used for projectors, and an important object is to provide improved electrodes for the same. It is known that the light yielded by these lamps, as well as the steadiness of the arc can be increased by the cross-sectional 15 area of the electrodes being reduced below the usual size. It is found in practice that the diminution of the cross-sectional area of the negative electrode alone suffices for obtaining the above mentioned result. Now 20 it is not at once possible, however, to maintain the operation of the lamp for a rather long period with such an arrangement. On account of its small cross-sectional area the 25 resistance of the negative electrode is so great that after a short time the electrode becomes red-hot along its entire length and is rapidly destroyed.

An important object of the invention is to overcome this defect.

30 In order that the invention may be clearly understood reference will be made to the accompanying drawing in which one embodiment is represented by way of example in elevation.

35 The above mentioned defect is removed in the following manner. The thin negative carbon rod *n* is covered with a jacket or casing *m* of copper or other suitable metal. The cross-sectional area of this good conducting metallic casing is chosen so large 40 that the cathode is not heated injuriously when the current passes through it. On the other hand the cross-sectional area of the carbon must be so dimensioned that the 45 metallic casing is removed as soon as it arrives in immediate proximity to the arc. If the negative carbon has a relatively large cross-sectional area which is approximately 50 equal to the sizes usual heretofore, parts of the melting metal pass into the arc, temporarily color its light and prejudicially influence the steadiness of the lamp.

The new arrangement according to this invention therefore differs substantially from former attempts to employ copper-plated 55 carbons, particularly by this source of disturbance being removed by the cross-sectional area of the negative carbon being reduced to from one third to a sixth part of the size customary heretofore, and by the 60 metallic casing being correspondingly increased in size. In this manner the result is obtained that the metallic casing is liquefied at a distance of from 2 cms. to 3 cms. from the arc and falls away in drops, so that 65 metallic vapors do not pass into the arc. How very much the cathode must be changed in this arrangement as compared with the form usual heretofore is readily understood when it is explained that the cross-sectional 70 area of the new negative carbon for 150 amperes, for example, amounts to only 0.8 sq. cms., whereas a standard cathode for this strength of current has a cross-sectional area of about 5 sq. cms. The advantages 75 of this new cathode are available both in the known horizontal arrangement of the carbons, and also in the arrangement represented in the accompanying drawing. In the latter case the positive electrode *p* is 80 horizontal and the negative carbon is arranged at an angle of about 60° to the horizontal. This slanting position of the cathode facilitates and promotes in a particularly high degree the dropping off of the 85 liquefied metal.

What I claim as my invention and desire to secure by Letters Patent is:

In an arc lamp, the combination of a negative carbon which is relatively much 90 smaller than the positive carbon, with a relatively thick metallic casing surrounding said negative carbon, substantially as described.

In testimony whereof I have signed my 95 name to this specification in the presence of two witnesses.

FRIEDRICH KALKNER.
